TO N. V. PHILIPS GLOEILAMPENFABRIEKEN, OF EINDHOVEN, NETHERLANDS, A
LIMITED LIABILITY COMPANY

RECTIFYING INSTALLATION

Application filed March 16, 1928, Serial No. 262,299, and in the Netherlands May 7, 1927.

The invention relates to a rectifying installation in which one or more resistance lamps are used, each of which is characterized by having mounted in it a plurality of 5 resistance wires of which at least two are designed for different current intensities.

Hereinafter these resistance wires will be called "variator resistance wires", inasmuch as they vary their resistance with the 10 temperature. When the current passing through the wire increases the temperature, the resistance will likewise increase, so that the total increase of current is limited. Therefore, such variator resistance wires are employed to keep the current in the electrical 15 apparatus constant.

The bulb in which said wires are mounted is properly called a "resistance lamp" or "variator".

According to the invention, one or more 20 resistance wires may be provided between the current-supply points, with one or more branches.

The rectifying installation according to 25 the invention comprises a multiphase rectifier and one or more high-tension coils in addition to the usual secondary transformer coil consisting of several parts, at least one resistance lamp according to the invention 30 being utilized for the resistances required.

Figure 1 of the accompanying drawings 35 represents resistance lamps, which may be used in the installation, according to the invention, the diagram of connections of the latter being represented by Figure 2.

Referring to Figure 1, resistance wires are mounted within a glass bulb 1 which optionally may contain a gaseous filling, 2 is a cap provided with the usual contact pins 11. According to this mode of realization, there are 40 two separate resistance wires 8 and 9 which are calculated for different current intensities. The current is supplied by a pole wire 3 to the resistance wire 8 and after passing through the latter it is carried away by a pole wire 6. To the wire 3 is secured a pole wire 4 which serves to supply current to the resistance wire 9, which is provided in the middle with a branch 7. After this branch 45 begins that part of the resistance wire 9 50

which is indicated by 9' and whose pole wire is denoted by 5. The wires 9 and 9' are so calculated that during the operation of the lamp currents of the same intensity flow through the said branches. 55

The four pole wires, 3, 5, 6 and 7 are electrically connected to the contact pins 11. A central rod 10 secured to a stem 12, carries four sets of supporting hooks 13 and 14 to which the resistance wires are secured. 60

Figure 2 represents diagrammatically a rectifier circuit arrangement according to the invention, which comprises a full-wave rectifier 27. To operate this rectifier, the primary coil 15 of a transformer is connected to a suitable source of alternating tension. The installation can be utilized for half-wave or full wave rectification. 65

The transformer is provided with three secondary windings. Of these windings 19 and 23 are adapted to produce an equal voltage, while the third winding 25 has a larger number of turns and produces a higher secondary voltage than do the windings 19 and 23. The windings 19 and 23 are used 70 for full wave rectification, while the winding 25 is used for half wave rectification in circuits including variator resistances, which circuits will be more fully explained hereinafter. 75

Thus it will be seen that for half wave rectification the windings 25 and 19 are connected in series, thereby ensuring a higher voltage output than would be available with the winding 25 alone. 80

By connecting the negative terminal of the battery to be charged to the negative point of connection 16, the battery is charged by means of full-wave rectified current, namely in the following manner: starting 85 from the positive terminal 18, the charging current flows through the battery via the point of connection 16, through the resistance 9, through the coil 19 and during one half wave of the alternating current from the anode 20 to the cathode 21, through a part of the heating current coil 22 and back to the positive terminal 18. During the other half-wave the current flows from the point 16 90 through the resistance 9', the coil 23, the 95

anode 24, the cathode 21 to the positive terminal 18. If a higher charging voltage has to be utilized, the negative battery terminal is connected to a point of connection 17, which is connected to a high tension coil 25. In that case the battery will be charged by one half-wave of the alternating current. The charging current flowing in this case, takes the following path: starting again 10 from the positive terminal 18, through the battery to be charged, through the coil 25, through the resistance 8, through the coil 19 from the anode 20 to the cathode 21 and back to the positive terminal 18.

16 According to the invention, the three resistances denoted by 8, 9, and 9' are assembled in a single lamp. The resistances 9 and 9' are traversed by currents of the same intensity and as such may consequently be used 20 the resistances denoted in Figure 1 by 9 and 9'. In that case the battery will be charged by one half-wave of the alternating current. The charging current flowing in this case, takes the following path: starting again from 25 the positive terminal 13, through the battery to be charged, through the coil 3', through the resistance 14, through the coil 2, from the anode 8 to the cathode 10 and back to the positive terminal 13.

30 According to the invention, the three resistances denoted by 5, 6 and 14 are assembled in a single lamp. The resistances 5 and 6 are traversed by currents of the same intensity and as such may consequently be used 35 the resistances denoted in Figure 1 by 9 and 9'.

What I claim is:

1. A rectifying installation, comprising a rectifier, a transformer containing a plurality of secondary windings each cooperating 40 with the said rectifier, said windings being adapted to produce currents of different voltages, each winding being mounted in series with a variator resistance wire, said resistance wires being arranged in one bulb.

45 2. A rectifying installation comprising a rectifier, a transformer having more than one secondary winding, said windings being adapted to produce currents of different voltages and a plurality of variator resistance wires, arranged in one bulb, each wire being mounted in series with a secondary transformer winding at least two of said wires having different dimensions.

50 3. A rectifying installation comprising a rectifier, a transformer having two secondary windings adapted to produce currents of equal voltages and another winding adapted to produce a current of higher voltage, each winding being mounted in series with a variator resistance wire, said wires being arranged together in one bulb.

55 4. A rectifying installation comprising a rectifier, a transformer having two secondary windings adapted to produce currents of equal voltage, each of said windings being

70 mounted in series with a part of a variator resistance wire, the transformer having another secondary winding adapted to produce a current of voltage higher than that of the currents produced by the first mentioned secondary windings, said high-voltage secondary winding being mounted in series with a variator resistance wire having other dimensions than the first mentioned resistance wire and arranged in one bulb with same.

75 5. A rectifying installation, comprising a rectifier; a transformer having two secondary windings adapted to produce currents of equal voltage; a variator resistance wire parts of which are mounted between said secondary windings, each of said windings being connected in series with the adjacent end of said resistance wire; another secondary winding on said transformer, said last-mentioned winding being adapted to produce a higher voltage than that produced by said first-mentioned secondary windings; a second variator resistance wire, to one end of which the said last-mentioned secondary winding 80 is connected in series, the other end of the said second variator resistance wire being connected to a terminal of the first-mentioned resistance wire; a single bulb in which said resistance wires are mounted, and a plurality of contact plugs on said bulb by means 85 of which contacts with the resistance wires may be obtained.

90 6. In a rectifying installation adapted for both full wave and half wave rectification, a thermionic rectifier, a transformer having two secondary windings adapted to produce currents of equal voltages, and each being connected in series with a variator resistance, said secondary windings and their corresponding variator resistances being connected in series with each other, and across said rectifier, in such manner that the effective voltage of the rectified output is substantially equal to the E. M. F. of either one of 95 said windings, and being adapted for full 100 wave rectification, a third secondary winding with the said transformer, a third variator resistance of higher ohmic value than said first-mentioned variator resistances, said third winding and one of said first-mentioned 105 windings being connected in series with said third variator resistance and across said rectifier, for half wave rectification, and a single 110 bulb in which said variator resistances are 115 disposed.

120 7. In a rectifying installation adapted for both full wave and half wave rectification, a thermionic rectifier, a transformer having two secondary windings adapted to produce currents of equal voltages, and each being connected in series with a variator resistance, said secondary windings and their corresponding variator resistances being connected in series with each other, and across said rectifier, in such manner that the effective 125 130

voltage of the rectified output is substantially equal to the E. M. F. of either one of said windings, and being adapted for full wave rectification, a third secondary winding for
6 said transformer adapted to produce a current of higher voltage than the first-mentioned secondary windings, a third variator resistance of higher ohmic value than said first-mentioned variator resistances, said
10 third winding being connected in series with said third variator resistance and across said rectifier, for half wave rectification, and a single bulb in which said variator resistances are disposed.

15 In testimony whereof I affix my signature,
at the city of Eindhoven, this 24th day of
February, 1928.

JOHANNES GYSBERTUS WILHELM MULDER.
